UNITED STATES PATENT OFFICE.

MARY T. TATUM AND ELIZABETH W. TYNDALE, OF SWARTHMORE, PENNSYLVANIA.

DESIGN FOR A DOLL.

57,396.

Specification for Design.

Patented Mar. 15, 1921.

Application filed December 30, 1920. Serial No. 434,145. Term of patent 14 years.

To all whom it may concern:

Be it known that we, MARY T. TATUM and ELIZABETH W. TYNDALE, citizens of the United States, residing at Swarthmore, in the county of Delaware and State of Pennsylvania, have invented a new, original, and ornamental Design for a Doll, of which the following is a specification, reference being had to the accompanying drawing, forming part thereof.

The figure is a front elevational view of a doll showing our new design.

We claim:

The ornamental design for a doll as shown.

MARY T. TATUM.

ELIZABETH W. TYNDALE.
